NEUTRALIZING HIGH-FREQUENCY PUSH-PULL AMPLIFIERS

Werner Buschbeck and Hans Prost, Berlin, Germany, assignors to Telefunken Gesellschaft für Drahtlose Telegraphie m. b. H., Berlin, Germany, a corporation of Germany

Application October 8, 1936, Serial No. 104,634
In Germany September 13, 1935

3 Claims. (Cl. 179—171)

It is known from German Patent 532,515 that the neutralization of high frequency amplifiers can be rendered independent of frequency in that not only the grid-anode capacity be neutralized, but also the cathode-grid capacity and the cathode-anode capacity. According to applicant's proposal, this neutralization circuit is improved to obtain a still better independence of frequency, in that not only the capacities of the tube, but also the inductances of the electrode lead-ins are reproduced in the neutralization branches.

For a better understanding of the invention, reference is made to the accompanying drawings, in which:

Figs. 1, 2 and 5 are circuit diagrams of a push-pull amplifier neutralized in accordance with our invention.

Fig. 3 is a portion of the bridge circuit of Fig. 2 arranged to show certain voltage relations.

Fig. 4 is a portion of the bridge circuit of Fig. 2 arranged to show other voltage relations between certain points and

Fig. 6 is a portion of the bridge circuit of Fig. 5 showing certain voltage relations.

An example of application to the push-pull circuit is shown in Fig. 1 in which only the tubes and the neutralizing branches are shown. This reproduction is carried out in the simplest manner in that a cold tube is used in the neutralizing, or a geometrically exact imitation with or without glass bulb.

It was found that especially in case of short waves, considerable difficulties are encountered owing to the passing of an electron current between cathode and grid and between cathode and anode. This electron current in fact, changes on the one hand the capacities between cathode and grid and between cathode and anode, owing to its space charge, and on the other hand, it produces a damping of the grid-cathode path and a negative damping of the anode-cathode path.

These conditions produce the following actions upon neutralization: The amplifier may be for example neutralized in that a high-frequency alternating potential is applied to the input terminals while the potential at the output is reduced to zero. If the tube is a non-heated tube, and a neutralizing-condenser forms an exact reproduction of the tube, the output potential is equal to zero, i. e., the stage is neutralized. Now if the tube is heated, so that a direct grid current flows, the output potential is no longer zero. However, neutralization can be reestablished by increasing accordingly the grid-cathode capacity

by the neutralizing-condenser. At larger grid currents, a matching of the reactances is no longer sufficient, and it would be necessary to provide corresponding damping for the grid-cathode path of the neutralizing-condenser, in order to reproduce in the neutralizing-branch the phase displacement produced by the grid current. This matching would however only be valid for a single operating condition.

Wholly equivalent conditions appear, if for carrying out the neutralization an alternating plate potential is applied to the output terminals, and the alternating grid potential at the input is suppressed.

Hitherto these influences of the electron current to the grid have been reduced in that sufficiently high capacities were connected in parallel to the electrode capacities so as to reduce the influence of the electrode capacities. This method is useless as such in case of ultra-short waves, since on the one hand the capacities must be maintained as low as possible, while on the other hand, the additional parallel capacities can be connected only across a considerable line section.

This invention relates to a means and method by which the detrimental influences of the grid-cathode path and anode-cathode path can be eliminated without prejudicing the operation especially at ultra-short waves. In accordance with the invention, the inductances of the electrode lead-ins and the corresponding inductances of the neutralizing-branches are so chosen that for the alternating grid potential there are formed other equi-potential points besides the output terminals (bridge diagonals) as well as all anode-cathode paths and the corresponding paths of the neutralizing branches. For the alternating plate potential, besides the input terminals (other bridge diagonals) also all grid-cathode paths and the corresponding paths of the neutralizing-branches are formed to effect equi-potential points, so that variations in these tube paths, cannot disturb the equilibrium of the bridge.

By the designation "electrode lead-ins" there is meant the connections inside and outside the tube to the electrodes. Although the inductances of the lead-ins situated within the tube could as such be dimensioned in accordance with the data according to the invention as discussed, from a practical point of view, the correct conditions will have to be assured by the connection of inductances outside the glass bulb, since for reasons connected with the manufacturing methods of the glass bulb, the electrode lead-ins will not always have the dimensions herein required.

While in the anode-neutralizing circuit solely the grid-cathode capacity and in the grid neutralizing circuit solely the anode-capacity can be formed into additional equi-potential points, 5 both conditions can also be fulfilled at the same time in case of the push-pull circuit. For this reason the full result can be obtained only when applying the invention to the push-pull circuit.

It should also be pointed out that the change 10 in the capacities by the space charge is not entirely without influence upon the neutralization, however in applying the invention its influence will be considerably reduced.

For a clearer explanation, the push-pull circuit according to Fig. 1 is redrawn in Fig. 2 in connection with the conditions of the bridge. The capacities are the electrode capacities assumed to be concentrated in the center of the electrodes, and the corresponding capacities of 15 the neutralizing-branches. The inductances designated by letters such as L_A , L_G and L_K are assumed to be concentrated in the electrode lead-ins (not especially shown in Fig. 1). As in all lines (in contrast to coils), they are not determined by the lines proper, but by the entire closed 20 circuit. When interrupting the cathode connections of all tubes, and neutro-branches, and when short-circuiting all capacities, C_{AG} the circuit starting at G_1 , Fig. 2, across A_1 , G_2 , A_2 and back 25 to G_1 furnishes a resultant inductance, namely, $4 \times (L_A + L_G)$. A closed circuit starting from A_1 across the anode of tube 1, the short-circuited capacity C_{AK} of tube 1, point K and "anode" a of the neutro-branch 1 and back, furnishes an 30 inductance $2 \times (L_A + L_K)$. A corresponding closed circuit from G_1 across K results in $2 \times (L_G + L_K)$. The three inductances L_A , L_G and L_K thus are 35 exactly defined.

In accordance with the invention, the inductances L_A , L_G and L_K and the corresponding inductances of the neutro-branches are so chosen 40 that when applying a potential to a bridge diagonal, not only the other bridge diagonals but also the electrode paths lying in the direction of these 45 other diagonals will have zero voltage. When applying an alternating grid potential to the points G_1 and G_2 an ordinary neutralizing circuit provides zero voltage between A_1 , K and A_2 . 50 Through proper choice of the inductances according to the invention, the voltages at all anode-cathode paths likewise become zero. The apparent resistance of the anode-cathode paths thus is of no importance to neutralization. This 55 will be readily understood, when considering that voltages (and hence also resistances) are applied to these paths. These alternating potentials have no effect at the terminals G_1 and G_2 .

On the other hand, when applying an alternating anode potential between A_1 and A_2 , not 60 only the voltages between G_1 , K and G_2 should be equal to zero, but also the voltages at all grid-cathode paths, so that also the condition of 65 the grid-cathode path is without influence upon the neutralization.

In the following equations it is to be understood that currents are indicated by the arrows and the values thereof by the letter J with suitable subscript, alongside the arrows.

In Fig. 3, one of the two tube systems is shown again. When applying an alternating grid potential $\frac{1}{2} U_G$ between K and G_1 , the voltage between K and A_1 is zero owing to the equilibrium 75 of the bridge, so that the same alternating grid

potential $\frac{1}{2} U_G$ lies between A_1 and G_1 , and which for A_1-G_1 and $K-G_1$ will be found as follows:

$$(1) \frac{1}{2} U_G = J_A \cdot \left(j\omega L_A - \frac{j}{\omega C_{AG}} \right) + j\omega L_G \cdot (J_A + J_K) \quad 5$$

$$(2) \frac{1}{2} U_G = J_K \cdot \left(j\omega L_K - \frac{j}{\omega C_{GK}} \right) + j\omega L_G \cdot (J_A + J_K) \quad 10$$

$$(3) J_A \cdot \left(j\omega L_A - \frac{j}{\omega C_{AG}} \right) = J_K \cdot \left(j\omega L_K - \frac{j}{\omega C_{GK}} \right) \quad 10$$

C_{AK} shall have zero voltage, so that therefore the voltages at L_A and L_K must be equal to each other, since for alternating voltages the points A_1 and K can be considered connected to each other: 15

$$(4) J_A \cdot \omega L_A = J_K \cdot \omega L_K \quad 20$$

$$(5) J_A = J_K \cdot \frac{L_K}{L_A} \quad 20$$

This value inserted in the third equation gives,

$$(6) \left(j\omega L_A - \frac{j}{\omega C_{AG}} \right) \frac{L_K}{L_A} = j\omega L_K - \frac{j}{\omega C_{GK}} \quad 25$$

$$(7) \frac{L_K}{L_A} = \frac{C_{AG}}{C_{GK}} \quad 25$$

Figure 4 shows the case for an applied plate potential, whereby the capacity C_{GK} is to be without voltage. 30

$$(8) \frac{U_A}{2} = J_K \left(j\omega L_K - \frac{j}{\omega C_{AK}} \right) + j\omega L_A \cdot (J_G + J_K) \quad 35$$

Between G_1-A_1 there exists the same voltage

$$(9) \frac{U_A}{2} = J_G \left(j\omega L_G - \frac{j}{\omega C_{AG}} \right) + j\omega L_A \cdot (J_G + J_K) \quad 35$$

C_{GK} will be without voltage when:

$$(10) J_K \cdot \omega L_K = J_G \cdot \omega L_G \quad 40$$

$$(11) J_K = J_G \frac{L_G}{L_K} \quad 40$$

$$(12) \left(j\omega L_K - \frac{j}{\omega C_{AK}} \right) \cdot \frac{L_G}{L_K} = j\omega L_G - \frac{j}{\omega C_{AG}} \quad 45$$

$$(13) \frac{L_G}{L_K} = \frac{C_{AK}}{C_{AG}} \quad 45$$

The two conditions furnish:

$$(14) L_A : L_G : L_K = C_{GK} : C_{AK} : C_{AG} \quad 50$$

which gives the proper dimensioning for this example in accordance with the invention. In practice these relations will be attained through test. 55

These relationships assume another form in case of tubes with concentric electrode lead-ins for the purpose of reducing the lead-in induction and for other reasons. The bridge circuit of a push-pull circuit with such tubes is shown in Fig. 5. 60

On the one side of the tube, the lines leading to grid and cathode and on the other side, the lines leading to anode and cathode are brought out concentrically arranged to each other. The principal difference as compared with the case shown in Fig. 2, resides in that the concentric lead-ins produce magnetic coupling between the electrodes. The counterinduction between two concentric tubings is equal to the self induction of the outer tubing. Fig. 6 shows one of the two tube systems of Fig. 5. In place of self inductions and capacities, the designations of the reactances are immediately indicated. 70 75

When applying an alternating grid potential, the points A₁, K₁ and K₂ have the same potential owing to the equilibrium of the bridge, in Fig. 6,

$$5 \quad (15) \quad \frac{U_g}{2} - X_g(J_1 + J_2 + J_3) = J_1(X_A - X_{AG}) + J_2 X_{M2} \\ = J_2(X_{K2} - X_{GK}) + J_1 X_{M2} - X_{GK} J_3 \\ = J_3(K_{K1} - X_{GK}) - X_{GK} J_2 - X_{M1}(J_1 + J_2 + J_3)$$

It follows from the above that:

$$10 \quad (16) \quad J_2(X_{K2} - X_{GK}) + J_1 X_{M2} - X_{GK} J_3 = \\ J_3(X_{K1} - X_{GK}) - X_{GK} J_2 - X_{M1}(J_1 + J_2 + J_3)$$

Now X_{AK} shall be without voltage, therefore:

$$15 \quad J_1 X_A + J_2 X_{M2} = J_2 X_{K2} + J_1 X_{M2} \\ J_2 = J_1 \frac{X_A - X_{M2}}{X_{K2} - X_{M2}}$$

By substituting the above value of J₂ in Equation (16) we obtain the following:

$$20 \quad J_3 = \frac{J_1(X_{M1} + X_{M2}) + J_1 \frac{X_A - X_{M2}}{X_{K2} - X_{M2}} (X_{K2} + X_{M1})}{X_{K1} - X_{M1}} \\ 25 \quad J_3 = \frac{J_1[(X_{M1} + X_{M2})(X_{K2} - X_{M2}) + (X_A - X_{M2})(X_{K2} + X_{M1})]}{(X_{K1} - X_{M1})(X_{K2} - X_{M2})}$$

By eliminating the currents and voltages there is:

$$30 \quad X_A - X_{AG} + X_{M2} \frac{X_A - X_{M2}}{X_{K2} - X_{M2}} = (X_{K2} - X_{GK}) \frac{X_A - X_{M2}}{X_{K2} - X_{M2}} + X_{M2} - \\ X_{GK} \frac{(X_{M2} + X_{M1})(X_{K2} - X_{M2}) + (X_{K2} + X_{M1})(X_A - X_{M2})}{(X_{K1} - X_{M1})(X_{K2} - X_{M2})} \\ 35 \quad X_A = \frac{X_{K2}[X_{AG}(X_{K1} - X_{M1}) - X_{GK}X_{M1}] + X_{M2}[X_{GK}(X_{K1} + X_{M2} + X_{M1}) + X_{AG}(X_{M1} - X_{K1})]}{X_{GK}(X_{K2} + X_{K1})}$$

The conditions for the zero voltage of the grid-cathode path at applied alternating plate potential are obtained by interchanging the indices 2 and 1 and A with G.

$$40 \quad X_G = \frac{X_{K1}[X_{AG}(X_{K2} - X_{M2}) - X_{AK}X_{M2}] + X_{M1}[X_{AK}(X_{K2} + X_{M1} + X_{M2}) + X_{AG}(X_{M2} - X_{K2})]}{X_{AK}(X_{K2} + X_{K1})}$$

In view of the fact that the tube capacities result from other requirements in general, among 45 the values X_G, X_{M1}, X_A, X_{K2} any two values thereof can be selected and their value so chosen that the two conditions are fulfilled thereby. In this connection the lead-in inductances may also 50 become negative, i. e., they may become capacities.

Having described our invention, what we claim as novel and desire to secure by Letters Patent is:

55 1. An amplifying stage comprising a pair of input terminals and a pair of output terminals, a pair of tube networks forming a push-pull circuit each of said tubes including an anode, a cathode and a grid electrode, inherent capacity between the tube elements comprising C_{AG} between said anode and grid, C_{AK} between said anode and cathode and C_{GK} between said grid and cathode, said tube networks including leads for connecting said tube elements in the circuit, inductance L_K in the lead from each cathode, inductance L_A in the lead from each anode and inductance L_G in the lead from each grid, said inductances being related to said capacities substantially in accordance with the proportion

$$L_A : L_K : L_G = C_{GK} : C_{AG} : C_{AK}$$

70 75 a pair of balancing networks composed of capacities and inductances substantially identical both as to arrangement and magnitude with said tube network capacities and inductances, whereby each of said balancing networks includes inductances L_K, L_A and L_G, and capacities C_{AG}, C_{AK} and C_{GK},

C_{AK} and C_{GK}, means connecting together the ends of the inductances L_K of the tube networks remote from the cathodes and the corresponding

ends of the inductances L_K of the balancing networks, means for connecting the end of the inductance L_A remote from the anode of one tube network and the corresponding end of inductance L_A of one balancing network together and to one of said output terminals, means for connecting the end of inductance L_A remote from the anode of the other tube network and the corresponding end of inductance L_A of the other balancing network together and to the other output terminal, means for connecting the end of inductance L_G

- means connecting together the ends of the inductances L_K of the tube networks remote from the cathodes and the corresponding ends of the inductances L_K of the balancing networks, means 5 for connecting the end of the inductance L_A remote from the anode of one tube network and the corresponding end of inductance L_A of one balancing network together and to one of said 10 output terminals, means for connecting the end of inductance L_A remote from the anode of the other tube network and the corresponding end of inductance L_A of the other balancing network together and to the other output terminal, means for connecting the end of inductance L_G of said 15 one tube network remote from the grid and the corresponding end of inductance L_G of said other balancing network together and to an input terminal and means for connecting the end of inductance L_G remote from the grid of said other tube network and the corresponding end of inductance L_G of said one balancing network together and to the other input terminal, whereby 20 voltage impressed between the output terminals produces no difference of potential either between the input terminals or across C_{GK} of either tube in spite of the existence of inherent inductance in said leads.
3. An amplifying stage comprising a pair of input terminals and a pair of output terminals, 25 a pair of tube networks forming a push-pull circuit each of said tubes including an anode, a cathode and a grid electrode, inherent capacity between the tube elements comprising C_{AG} between said anode and grid, C_{AK} between said anode and cathode and C_{GK} between said grid and cathode, said tube networks including leads for connecting said tube elements in the circuit, inductance L_K in the lead from each cathode, in-

ductance L_A in the lead from each anode and inductance L_G in the lead from each grid, and wherein the following proportion is satisfied $L_A:L_K=C_{GK}:C_{AG}$, a pair of balancing networks composed of capacities and inductances substantially identical both as to theory and magnitude with said tube network capacities and inductances, whereby each of said balancing networks includes inductances L_K , L_A and L_G , and capacities C_{AG} , C_{AK} and C_{GK} , means connecting together the ends of the inductances L_K of the tube networks remote from the cathodes and the corresponding ends of the inductances L_K of the balancing networks, means for connecting the end of the inductance L_A remote from the anode of one tube network and the corresponding end of inductance L_A of one balancing network together and to one of said output terminals, means for connecting the end of inductance L_A remote from the anode of the other tube network and the corresponding end of inductance L_A of the other balancing network together and to the other output terminal, means for connecting the end of inductance L_G of said one tube network remote from the grid and the corresponding end of inductance L_G of said other balancing network together and to an input terminal and means for connecting the end of inductance L_G remote from the grid of said other tube network and the corresponding end of inductance L_G of said one balancing network together and to the other input terminal, whereby voltage impressed between said input terminals produces no difference of potential either between the output terminals or across C_{AK} of either tube in spite of the existence of inherent inductance in said leads. 30
